CLAIM

The ornamental design for a mixing and casting table, substantially as shown and described.

DESCRIPTION

FIG. 1 is a front elevational view of the mixing and casting table, showing my new design.

FIG. 2 is an end view of the mixing and casting table.

FIG. 3 is a plan view illustrating the top of the mixing and casting table and showing my design;

FIG. 4 is an end view opposite to that of FIG. 2, illustrating the design of my mixing and casting table.

FIG. 3

FIG. 4
